UNITED STATES PATENT OFFICE.

CALVIN OVERDORFF AND JOHN JUHASZ, OF JOHNSTOWN, PENNSYLVANIA.

AIR COMPRESSOR.

Application filed February 17, 1927. Serial No. 169,096.

The present invention consists of an air compressor and is designed to compress the air in a facile, expeditious, and inexpensive manner to make the compressed air available as a motive agent without recourse to expensive or fragile apparatus for this purpose.

Additional objects of the invention are to provide a compressor which automatically operates under pressure of water inducted into the compressor chambers, only a single water inlet pipe being used to supply both chambers of the compressor, the supply being selective by use of an automatically operated valve; to provide pressure-operated check valve mechanism which coacts with the selective valve means to operate the latter for closing off the water supply in either chamber when a predetermined height has been reached; and to provide durable apparatus which requires no adjustment or replacement.

Other objects of the invention will be apparent from the following description of the present preferred form of the invention taken in connection with the accompanying drawings, wherein

Fig. 1 is a longitudinal fragmentary sectional view of a compressor constructed in accordance with the present invention;

Fig. 2 is a vertical sectional view of the same; and

Fig. 3 is a fragmentary perspective view of one end of the selective valve releasing lever.

The compressor of the present invention embodies twin chambers or cylinders 5, each of which, in the present instance, is shown to be of cylindrical configuration and has the outer end thereof closed, as indicated at 6, and the inner end opened and provided with a peripheral flange 7 which has a series of bolt-receiving openings therein. The flanged ends of the chambers are detachably engaged to the opposite faces of a partition or head 8, which is used to separate the chambers. The upper end of the partition or head has an inlet opening 9 formed therein, which detachably receives one end of a water supply pipe 10 through which the water is injected under pressure. The inner end of the opening 9 communicates with a transverse opening formed in the partition 8, in which a bushing 11 is mounted, the ends of the latter projecting beyond the opposite faces of the partition. The bushing

is provided with an inlet opening which complements the inlet opening 9 for communication with the inlet pipe 10. A selective valve 12 is slidably mounted in the bushing 11 and conforms to the contour of the latter. The valve is equipped with a duct or way 13, the ends of which open through the periphery of the valve into the chambers 5. Inlet ways 13' communicate with an intermediate part of the duct 13 and are selectively registerable with the inlet opening 9 in a manner more fully hereinafter set out. Communication is, in this way, established between the pipe 10 and chambers 5 so that water injected through the pipe 10 will flow into either one of the chambers depending upon the position of the valve 12.

It is desired that the valve 12 be automatically operated so that communication between the water supply pipe and either chamber will be cut off when the water in the chamber reaches a predetermined height, and with this in view we have provided mechanism which coacts with the valve.

The mechanism of each chamber embodies a rightangle bar 14, which is detachably mounted on one face of the partition 8 so that the upper edge thereof supports the extended terminal of the bushing 11. The bar has pivotally mounted thereon a bell-crank lever 15, the upper terminal of which is bifurcated as indicated at 16 and adapted to receive pintles 17 which project laterally from the opposite ends of a trigger 18. Each trigger has the inner end thereof pivotally engaged with one end of the valve 12 as advantageously illustrated in Fig. 1; the opposite end thereof projects outwardly for engagement in a recess 19 formed in the upper marginal edge of the bar 14.

The outer terminal of the lower end of the bell-crank lever 15 is pivotally engaged with one end of a link 20, the opposite end of said link being pivotally engaged with the upper end of a check valve 21, the latter being slidably engaged with the outer face of the partition 8 at the bottom of the latter for engagement over a transversely extending passageway 22, which is formed in the partition.

The mechanism for operating the valve 12 further includes a supporting base 23 which has a standard 24 upstanding on its outer end and slidably engaged by a float 25, 110 which latter has a sleeve concentrically mounted therein upon which rollers 26 are

mounted. The rollers are movable across the upper margin of a trigger release lever 27, the inner end of which is pivoted on the bar 14 as indicated at 28. The inner end 5 of the lever 27 has a portion of its upper margin removed to provide an inclined face 29 which is adapted to bear against the outer terminal of the trigger 18 for projecting the latter from the recess 19 when the float 25 10 gravitates to the lower end of the standard 24.

The water passage-way 22 in the lower end of the partition 8 communicates with the water outlet opening 30 which, in turn, 15 receives one end of a water outlet pipe 31. It will be noted upon reference to Fig. 1 of the drawings that when one of the valves 21 is in a closed position across the passage-way 22 the other valve is in an open position 20 so that communication is at all times established between one of the chambers and the outlet water opening 30 and between the other chamber and the inlet water opening 9.

25 Each of the chambers is provided, preferably in the top thereof, with an air outlet opening 32 which communicates with a corresponding opening formed in the bottom of an air dome 33, the upper end of the latter issuing into a pipe 34 which is adapted to communicate with an air storage tank in a manner well known in the art. Each air dome has a valve 35 floatingly mounted therein through which a pin 36 extends, the 30 upper end of the latter being pointed for snug engagement with a valve seat 37 which is formed in the inner end of the pipe 34. It will be apparent that as the water rises in each chamber the air in the latter will be 35 forced outwardly through the opening 32 around the valve 35 and through the pipe 34 until the water reaches a predetermined height, at which point the valve closes on its seat in an apparent manner.

40 45 Air is taken into each of the chambers through inlet pipes 38, each of which is equipped with a non-return valve of conventional design.

In operation, assuming that the parts of 50 the compressor are in the position shown in Fig. 1, communication is established between the water inlet pipe 10 and the chamber 5 through one of the inlet ways 13' and duct 13. As this chamber fills up the float 25 is urged upwardly on the standard 24, thereby 55 permitting the inner end of the lever 27 to be moved downwardly. The trigger 18 correspondingly gravitates until a depending right-angle extension on its terminal impinges against an abutment or stud 27'. Engagement of the trigger 18 with the abutment 27' prevents the trigger from being locked for movement beyond a lug 28' formed on the top edge of the member 14. 60 65 This leaves the valve 12 free to move under

70 pressure of the water in the chamber being filled. As the valve 12 is urged over through the bushing 11 the inlet ways 13' and outlet ways of the duct 13 will change position to permit the other chamber to refill and the filled chamber to empty.

Attention is directed to the fact that the construction of the present mechanism is such that communication will not be established between the water supply pipe and 75 the empty chamber until the filled chamber has reached a predetermined height due to the fact that although the rising of the float in the chamber being filled holds the trigger in that chamber in a released position, the trigger in the unfilled chamber is held in a locked position against its lug 28' since release of the trigger in the unfilled chamber is not accomplished until the float in the unfilled chamber reaches its lowermost position, at which time the arcuate inner end 29 of the lever 27 in the unfilled chamber raises the trigger in the unfilled chamber until it clears the lug 28', thereby permitting the pressure of water in the filled chamber to 80 move the valve over. This makes the valve positive in its operation and eliminates any possibility of the two chambers being simultaneously filled.

85 It is apparent that while the valve 12 is being urged from one position to another the check valves 21 will be correspondingly operated so that the check valve in the chamber being filled is in a closed position over the outlet passageway 22 and the check valve in the other chamber in an open position. It is believed to be apparent that while a chamber is being filled with water the air therein is expelled outwardly through the dome 23 and induced into an air storage 90 tank or the like. Operation of the compressor is controlled by a valve 39 in the supply pipe 10.

95 We have found that by use of a compressor constructed in accordance with the invention herein described it is possible to compress air in appreciable volume and inexpensively so that compressed air may be used to a greater extent as a commodity. In view of the rapidity with which the 100 air may be compressed it is unnecessary to provide cumbersome storage tanks and the parts of this compressor are such that adjustment or replacement thereof is unnecessary.

105 It is furthermore, of course, to be understood that although we have herein shown and described twin chambers these may be multiplied to satisfy practically any need. Moreover, we are aware that various changes 110 may be made in the invention within the scope of the claims hereto appended.

115 We claim:

120 1. An air compressor including twin chambers provided with air inlet and outlet

- openings and equipped with an interposed partition provided with a water inlet opening at the top and a water outlet opening in the bottom, a pressure operated valve slidably mounted in the partition to close communication through the inlet opening and provided with a pair of ducts singly alignable with the inlet opening to establish communication between the latter and one of the chambers, mechanism mounted on each side of the partition and engaged with the opposite ends of the valve including valves alternately slideable across the outlet opening in response to the movement of the first-mentioned valve when a predetermined water level is reached in each chamber.
2. An air compressor including twin chambers, each provided with a non-return inlet opening and a non-return outlet opening, a partition mounted between said chamber and provided with a water inlet opening which communicates with both chambers, a valve slidably mounted in the partition across said opening to close communication through the latter and provided with a duct to establish communication between the inlet opening and one of the chambers for selectively filling the chambers, and means mounted in each chamber and engaged with one end of the valve and movable by the rise and fall of water in the chambers to automatically control the movement of the valve.
3. An air compressor including a head equipped with chambers on the opposite sides thereof which are provided with air inlet and air outlet openings, said head being provided with a water inlet opening which communicates with both of said chambers and a water outlet opening which communicates with both chambers, a valve slidably mounted in said head to close communication through said inlet opening and provided with a duct with spaced inlet ways, either of which may be engaged with the inlet opening to establish communication therebetween and one of the chambers, means mounted on each side of the head and engaged with said valve and automatically operated by the rise and fall of water in the chambers to release the valve and permit movement thereof under pressure of water in one of the chambers only after water has been completely expelled from the opposite chamber.
